UNITED STATES PATENT OFFICE

GEORGE EDWARD MORROW, OF ENID, OKLAHOMA

WINDOW SASH ADJUSTER

Application filed September 4, 1930. Serial No. 479,743.

The present invention relates to a window sash adjuster and has for its prime object to provide an automatic adjusting structure to keep window sashes in perfect working condition at all times and when both sashes are closed and locked, with a standard sash lock, to form a window that is practically air, water and dustproof.

Another very important object of the invention resides in the provision of a device of this nature which is exceedingly simple in its construction, and in the combination and arrangement of parts as will be hereinafter more fully described and claimed.

15 In the drawings:

Figure 1 is an elevation of a window embodying the features of my invention,

Figure 2 is a vertical section taken substantially on the line 2—2 of Figure 1,

20 Figure 3 is a horizontal section taken substantially on the line 3—3 of Figure 1,

Figure 4 is a perspective view of the metal casing or slide,

25 Figure 5 is a perspective view of one of the bowed springs, and

Figure 6 is a perspective view of the top casing member.

Referring to the drawings in detail it will be seen that numerals 1 represent sections of the wood sash stop. Numerals 4 denote sections of metal casing or slides and numerals 2 denote the bowed spring therein. Each casing or slide 4 comprises a plate *a* having a plate *b* extending perpendicularly therefrom along the medium longitudinal dimension thereof and having a lateral extension *c*. The ends of the bowed spring bear against the plate *b* and against the stop 1 so as to force the casing against the sash 10.

40 Numeral 11 denotes another casing which is disposed adjacent the top 1' and includes a plate *a'* having a plate *b'* extending perpendicularly from the medium longitudinal dimension thereof and merging into an obliquely disposed section *b''* to form a bevel and this section *b''* merges into an extension *c'*. A spring 2 is associated with the section 11.

50 The following are the instructions for installing my improved structure.

A small groove is made in the wood stops underneath the side next to the sash run to receive the casing on slides 4 and 11. On the edge of the stop is placed the steel spring 2 held in place in any suitable manner. The 55 metal casing or slide is then placed over the spring and edge of the stop. When the sash is in proper position, place the stop and adjuster so as to allow about three sixteenths of an inch play.

60 The springs being of proper strength and tension, the sash will always be held firmly against the middle stop, will slide freely and can always be operated. The metal springs 9 when tacked on the bottom of cross rail of top sash forms a tight joint between the upper and lower sash when locked. The metal sheet spring 9 is tacked to the back edge of the window stool. The wide angle extends under the bottom of the lower sash and when the 70 window is locked a tight joint is formed.

65 The screws and washers 8 are placed above the casing on the inside and below the casing on the outside to prevent same from sliding endwise. A slight curve in that part of the metal casing that occupies the back of the sash run or groove forms a spring cushion for the edge of the sash, which not only helps to seal the window more tightly but takes care of expansion and contraction at that point. 80 The device can be made of any kind of material and of any size and weight that may seem most desirable.

75 The bevel extension *b''* is provided for the closing of the upper sash as will be quite 85 apparent.

When necessary a groove or rabbet can be made on the outside of upper sash to provide the necessary play for the device. The casings or slides for upper sash should be properly notched, when necessary, so same will not interfere with sash pulley.

90 From the above detailed description, it will be seen that I have devised an automatic window sash adjuster which will keep the window sash in perfect working condition at all times and when both sashes are closed and locked to form a window that is practically air, water and dust proof. As is well known, 95 it is very common to find window sashes that 100

cannot be operated. The two chief causes are expansion, or swelling in damp weather and sticking caused by paint, varnish, etc. My structure will not only take care of this trouble but also will take care of any contraction which might occur, causing more water, wind and dust to enter, and also causing much annoyance from rattling.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. An adjuster of the class described including a casing formed with a plate having a plate extending perpendicularly from a medium longitudinal dimension and merging into a laterally extending plate.

2. An adjuster of the class described including a casing formed with a plate having a plate extending perpendicularly from a medium longitudinal dimension and merging into a laterally extending plate, and a bowed spring inside the casing to bear against the perpendicular plate.

3. In combination with a sash and a frame, a stop on the frame having a recess adjacent the frame, a casing interposed between the sash and the frame and the stop, said casing comprising a plate lying alongside of the casing and extending into the recess and between the casing and the sash and having a plate disposed perpendicularly thereto from along a medium longitudinal dimension and merging into a lateral plate extending along the outside of the stop, and spring means in the casing bearing against the perpendicular plate and the stop.

4. In combination with a sash and a frame, a stop on the frame having a recess adjacent the frame, a casing interposed between the sash and the frame and the stop, said casing comprising a plate lying alongside of the casing and extending into the recess and between the casing and the sash and having a plate disposed perpendicularly thereto from along a medium longitudinal dimension and merging into a lateral plate extending along the outside of the stop, and spring means in the casing bearing against the perpendicular plate and the stop, said spring being of the bowed type.

5. In combination with a sash and a frame and an elongated plate bent to provide a portion for engaging the frame and located between an edge of the sash and the frame, a second portion engaging the outer face of the stop and an intermediate portion connecting the first two portions together and a spring located between the intermediate portion and the stop for holding said intermediate portion against a part of the sash.

In testimony whereof I affix my signature.

GEORGE EDWARD MORROW.
